UNITED STATES PATENT OFFICE.

JAMES DRAPER, OF SAN JUAN, PORTO RICO.

REISSUED

WASHING APPARATUS.

Application filed July 15, 1922. Serial No. 575,162.

To all whom it may concern:

Be it known that I, JAMES DRAPER, a citizen of the United States, residing at San Juan, Bayamon, Porto Rico, have invented 5 new and useful Improvements in Washing Apparatus, of which the following is a specification.

This invention relates to washing apparatuses.

10 More particularly the invention relates to machines used for washing, boiling, and rinsing clothes and the like capable of withstanding heavy internal pressure.

Some of the objects of the present invention are:—to facilitate the introduction of clothes to be washed into the machine and the removal thereof from the washing machine; to equip the shell of the machine which encloses the clothes-cylinder, with 15 doors at the opposite ends thereof, and means with which the doors may be opened and closed in unison with the introduction and removing of the clothes-cylinder; to include in the machine construction means 20 whereby the rotation of the clothes-cylinder will be made easy; to employ in conjunction with the washing machine a clothes-cylinder having traction surfaces, bogies, which embody means which co-acts with said traction 25 surfaces for effecting the translation of the clothes-cylinder into the machine, and the translation of the clothes-cylinder from the machine; and with these and other objects 30 in view, the invention resides in the particular combination, operation and function 35 of the parts hereinafter fully described and illustrated in the accompanying drawing, in which:—

Figure 1 is a diagrammatic view of the 40 apparatus of the present invention and illustrating the manner in which the clothes-cylinders are introduced into and removed from the shell of the washing machine.

Figure 2 is a side elevation.

45 Figure 3 is a plan view.

Figure 4 is a transverse sectional view taken on the line 4—4, of Figure 2.

50 Figures 5 and 6 are detail views respectively of features of the door opening and closing mechanism.

55 Referring now to Figure 1, it will be apparent that, the present apparatus will comprise, generally, a washing machine 10, and bogies 11. The machine 10 is of a type having a clothes-cylinder which is capable of

being introduced into the machine 10 with the clothes therein for the washing, boiling and rinsing operations; and to be removed from the machine after the said operations. To this end means is employed on each of 60 the bogies 11, on the said clothes-cylinder and also interiorly of the clothes-cylinder receiving shell of the machine whereby the clothes-cylinder may be rolled from a bogie into the said shell or from the said shell into 65 a bogie. The means with which the translation of the clothes-cylinder is effected will be set forth more fully hereinafter.

The machine 10 includes an outer shell 12 having doors 13, 13 at the opposite ends 70 thereof. The shell rests on suitable supports or bearings 14. Suitable pipes are employed for introducing the cleaning agent and water as well as a suction action in carrying out the washing, boiling and rinsing 75 operations. Arranged interiorly of the shell 12 are annular members 15 which are held against displacement by members 16 attached to the shell. Each of the members 15 is capable of rotation and actually rotates on 80 anti-friction balls 17. Each member 15 has attached thereto rollers 18. In the present instance there are four rollers arranged in pairs diametrically opposite each other. As stated, the shell 12 has doors 13, 13 and in 85 order that the said doors may be opened in unison mechanism, presently described, is employed. A gear 19 rotatable on a shaft 20 mounted in suitable bearings 21, has attached thereto a suitable crank member 22. 90 If desired the gear 19 may have connection with a pulley. An idler gear 23 is employed in mesh with the teeth of gear 19 and the teeth of a gear 24 secured to the shaft 20. This arrangement gives certain leverage and 95 facilitates rotation of the shaft 20. The shaft 20 also has a gear 25 attached thereto which meshes with the teeth of rack members 26, 26 each of which has connected thereto a rod 27. Each door 13 has arranged 100 thereon in suitable bearings a bar 28 one end of which is engageable in a plate 29 while the opposite end is connected as at 30 to a pivotally mounted member 31. The members 31 are connected respectively to the rods 105 27 by links at 32. Each of the doors is hingedly mounted as at 33.

It will now be manifest that by rotating the gear 19 and by virtue of the intervention of the parts just mentioned, the doors may 110

be moved to open and close the opposite ends of the shell 12, and in their closing position are held by the bars which are then in engagement with the plates 29. The machine 5 10, as stated, includes a clothes-cylinder 35 which is made up of a foraminated material so formed as to provide agitating members 36 of which there are four in number arranged in pairs at right angles. The said 15 members 36 are formed to extend interiorly of the cylinder 35 and defined ways 37 in each of which is formed traction surfaces 38, 38. The construction of the clothes cylinder 35 therefore is such that it may be supported upon the rollers 18 carried by the annular members 15. It follows, that the clothes-cylinder 35 will not only rotate with the members 15 but that the same may be moved longitudinally with respect to the 20 shell on the rollers 18. The clothes-cylinder is reversely rotated by the employment of a belt or cable 39 which is passed over a driven pulley 40. The belt or cable 39 passes through suitable openings in the 25 shell 12 and in order to prevent the escape of steam and water a casing 41 is employed which encloses the leads of the belt or cable and the pulley 40 is shown in Figure 4.

Inasmuch as the clothes-cylinder when 30 loaded is of considerable weight it has been found necessary to employ the bogies 11. Each bogie has rollers 45. The rollers are so disposed that when the bogie is brought in proper juxtaposition to the shell 12 the clothes-cylinder, as the case may be, may be rolled from the rollers of the bogie to the 35 rollers 18 of the members 15, or from the rollers 18 to rollers 45 of the bogie.

It will now be manifest that by reason of 40 the utilization and employment of parts hereinbefore described the handling of the clothes for the washing thereof is facilitated, that the several operations to the clothes may be carried out effectually.

45 The washing, boiling and rinsing of the clothes is accomplished in part by virtue of the pipes 50, 51, 52, 53 and 54. The pipes 50 and 51, respectively, serve for the introduction of hot and cold water; the pipe 52 50 serves for the introduction of steam; the pipe 53 is an outlet for the water and sediment; and the pipe 54 is connected to a vacuum creating device for creating a vacuum in the shell. By creating a vacuum in 55 the shell of the machine with the washed

clothes therein, the clothes will be thoroughly dried.

It will now be manifest that the apparatus not only affords means for readily handling the clothes, but that rehandling of 60 the clothes is obviated since all of the operations to the clothes including the drying operation is done in the same machine.

What is claimed is:

1. A washing machine comprising a shell 65 having doors at the opposite ends thereof, bodily movable rollers on the inside of said shell, and a clothes-cylinder having traction surfaces which coact with said rollers in the movement of the clothes-cylinder into and 70 out of said shell.

2. In a washing machine having a stationary cylinder, a foraminated clothes-cylinder, means carried by the stationary cylinder on its wall circumferentially thereof 75 on which the clothes-cylinder rotates, said means including anti-friction devices.

3. In a washing machine having a stationary shell having closures at the opposite ends thereof capable of being moved to render the opposite ends of the shell open, a foraminated clothes-cylinder having agitating members interiorly thereof and ways and traction surfaces, the said clothes-cylinder being rotatably mounted when disposed interiorly of said shell, and supporting means including rollers which are accommodated by said ways and traction surfaces, the rollers and traction surfaces co-acting to allow the longitudinal movement of the clothes-cylinder with respect to the 90 shell.

4. In a washing machine, a stationary shell having closures at the opposite ends thereof and capable of being moved to render the opposite ends of the shell open, a 95 clothes-cylinder having a reticulated wall, ways formed in said wall and extending longitudinally thereof, traction surfaces in said ways, members located interiorly of said shell for rotational movement, rollers 100 carried by said members, the said clothes-cylinder being supported on said rollers when disposed in said shell, the rollers co-acting with said traction surfaces for the movement of said clothes-cylinder on said 105 rollers.

In testimony whereof I have affixed my signature.

JAMES DRAPER.
